UNITED STATES PATENT OFFICE.

HARRY LANSING CAREY, OF RICHMOND HILL, NEW YORK.

DIRIGIBLE TRAFFIC INDICATOR.

Application filed November 23, 1921. Serial No. 517,157.

To all whom it may concern:

Be it known that I, HARRY LANSING CAREY, a citizen of the United States, and a resident of Richmond Hill, county of Queens, 5 and State of New York, have invented certain new and useful Improvements in Dirigible Traffic Indicators, of which the following is a specification.

The object of my invention is to attain 10 a simple dirigible traffic-indicating device of facile manipulative character adapted to the various exigencies and requirements of use on road vehicles generally, and particularly suitable for installation on automobiles and analogous motor-driven carriages, trucks, etc.,—an indicator that will be effective at night as well as during the day, as and for the reasons hereinafter fully set forth,—the invention consisting in the 15 specific construction, arrangement and combination of parts described and claimed, and distinctive features being the rotative means employed, and the method of attaining internal illumination and the diffusive transmission of light rays, whereby the device is rendered essentially self-contained and semi-automatic in nature and function, substantially as illustrated in the accompanying drawings and exemplified in the text explanatory thereof, similar reference letters and numerals being used throughout to designate the parts.

In the said drawings,

Fig. 1, is a side elevation of my improved 35 traffic indicator;

Fig. 2, is a central vertical sectional elevation taken upon plane of line 2, 2, Fig. 8;

Fig. 3, is a horizontal section of the pointer head taken upon plane of line x—x, Figs. 40 1 and 2, only on a smaller scale, and with the electric light bulb and other details omitted;

Fig. 4, is a detail elevation of the rotative spindle;

Fig. 5, is a sectional detail of the fixed base post in and on which the rotative indicator spindle is mounted;

Fig. 6, is a transverse section taken upon plane of line 6—6, Fig. 2, looking in the direction of the arrows;

Fig. 7, is a detail of the fixed base post cap;

Fig. 8, is a top view of my traffic indicator upon the same scale as that of Fig. 3;

Fig. 9, is a diagrammatic detail indicat-

ing the positioning of my indicating device on an auto-radiator inlet.

My pointer head A, is of arrow configuration, aside from which a distinctive feature is the axial illuminative means e, thereof in 60 conjunction with its side light apertures a, a, arranged convergent to the central longitudinal line or plane of horizontal rotation, whereby the light emanating from the pointer head A, when the latter is illuminated, 65 will visually indicate traffic conditions or intentions.

Thus, it will be seen by reference particularly to Figs. 1 and 2, of the drawings, that all the light apertures or slots a, a, are 70 convergent toward the central horizontal line x, x, and in the direction of the point of the arrow head, so that at night illuminated slots a, a, will clearly indicate direction of point in accordance with the position assumed by 75 or imparted to the pointer head A.

The latter is preferably made in concavo-convex half sections which may be screwed together as illustrated in the drawings, or otherwise secured together and upon the 80 upper end of the rotative tubular spindle S, in said upper extremity of which the socket e', for the electric lamp e, is mounted, as indicated more particularly in Fig. 2. This feature of medially and axially positioning 85 the electric light e, within the rotative pointer head A, is an important factor in my construction and arrangement of parts, in that the light is thereby diffused in both directions, and thus effectually illuminates 90 both the front and rear cavities of the head, rendering the slots a, a, conspicuous and effective for the purpose desired.

The wiring for the electric lamp e, extends through the hollow spindle S, and may connect with the head light wiring, or with the rear or tail light wiring as the case may be, my indicator being adapted for installation and use at both the front and rear of an automobile or similar motor driven vehicle. 100

The spindle S, is rotatively mounted in and upon a fixed base post B, which may be attached to a radiator inlet neck as indicated in Fig. 9, or otherwise permanently positioned at the front or rear of a car, as and 105 by means which may be found most expedient.

A retractile spring R, is interposed between the spindle S, and the base post B, in such manner that it tends constantly to 110

hold the said spindle in retracted normal position with the head A, pointing forward, in which position a stud s, on the spindle S, rests against a fixed part b, on and in the 5 base post B, said fixed part, in the construction shown by way of exemplification in the drawings, consisting of an arm (b) pendent from the cap piece d', attached to and closing the upper end of said base post B, said 10 cap piece b', also acting as a bearing for the medial portion of the spindle S, as shown in Fig. 2,—the lower contracted portion s', of said spindle being step-supported on the bottom plug b², inserted in the lower 15 end of the base post B. In this construction I also utilize the pendent arm b, to fixedly hold one (the lower) extremity of the retractile spring R, in this case consisting of a coiled spring, the upper extremity of which 20 is positioned and held in a filler s³, in the lower portion of the tube which constitutes the upper portion of the rotative spindle S, also as shown in said Fig. 2, of the drawings.

The spindle S, is manually rotated against 25 the resistance of the coiled retractile spring R, by any suitable means, as by a flexible ligament s^x, secured to the lower end of the spindle S, with one or more convolutions wrapped therearound, said flexible ligament 30 protruding through an aperture b², formed for the purpose in the lower side wall of the base post B, and being of sufficient length to extend to a point and means within the control of the driver for manipulative purposes.

35 What I claim as my invention and desire to secure by Letters Patent is,

1. As an article of manufacture, a dirigible traffic indicating device of the character designated, comprising a hollow rotative arrow-shaped pointer made in concavo-convex half sections formed with light slots convergent to the axial line of pointive direction, means for clamping said pointer to a hollow rotative spindle, said spindle, 40 and an electric lamp internally positioned in said pointer in alignment with its axis of rotation, and manually controlled means for effecting the rotative movement of said spindle and pointer, substantially in the 45 manner and for the purpose described.

2. As an article of manufacture, a dirigible traffic indicating device of the character designated, comprising a hollow rotative arrow-shaped pointer made in concavo-convex half sections formed with light slots convergent to the axial line of pointive direction, means for clamping said pointer to a hollow rotative spindle, said spindle, and an electric lamp internally positioned in said pointer in alignment with its axis of rotation, together with means for rotating said spindle and pointer, substantially 50 in the manner and for the purpose described.

3. As an article of manufacture, a dirigible traffic indicating device of the character designated, comprising a hollow rotative arrow shaped pointer made in concavo-convex half sections formed with light slots convergent to the axial line of pointive direction, means for clamping said pointer to a hollow rotative spindle, said spindle, and an electric lamp internally positioned in 55 said pointer in alignment with its axis of rotation, a retractile spring arranged to constantly tend to hold said spindle in normal position, and means for manually rotating said spindle against the resistance of said 60 retractile spring, substantially in the manner and for the purpose described.

4. As an article of manufacture, a dirigible traffic indicating device of the character designated, comprising a hollow rotative arrow-shaped pointer made in concavo-convex half sections formed with light slots convergent to the axial line of pointive direction, means for clamping said pointer to a hollow rotative spindle, said spindle, 65 and an electric lamp internally positioned in said pointer in alignment with its axis of rotation, and manually controlled means for effecting the rotative movement of said spindle and pointer, substantially in the 70 manner and for the purpose described.

HARRY LANSING CAREY.
